UNITED STATES PATENT OFFICE

HARRY H. HONIGBAUM, OF NEW YORK, N. Y.

DESIGN FOR A HANGER

Application filed May 11, 1929. Serial No. 31,179. Term of patent 14 years.

To all whom it may concern:

Be it known that I, HARRY H. HONIGBAUM, a citizen of the United States, residing at New York city, county and State of New York, have invented a new, original, and ornamental Design for Hanger, of which the following is a specification, reference being had to the accompanying drawing, forming part thereof.

The figure is a perspective view of a hanger showing my new design.

I claim:

The ornamental design for a hanger, as shown.

HARRY H. HONIGBAUM.
